UNITED STATES PATENT OFFICE.

VASIL MACKAY, OF BOSTON, MASSACHUSETTS.

FURNACE.

1,221,073.

Specification of Letters Patent.

Patented Apr. 3, 1917.

Application filed February 18, 1914. Serial No. 819,320.

To all whom it may concern:

Be it known that I, VASIL MACKAY, a citizen of the United States, residing at Boston, in the county of Suffolk and State of Massachusetts, have invented new and useful Improvements in Furnaces, of which the following is a specification.

This invention relates to improvements in furnaces and more particularly to furnace 10 grates and means for operating said grates to automatically feed fuel and uniformly spread the same thereover, or to shake the ashes and break up clinkers and fuel.

An object of this invention is to provide 15 a grate having a plurality of pivoted grate-bars which may be manually operated or operated by power driven means to feed fuel thereover from end to end, or be operated to discharge the fuel therefrom.

20 Another object of the invention is to provide means adapted to vary the inclination of said grate, whereby the feeding of the fuel thereover may be advanced or retarded.

The invention consists in the combination 25 and arrangement of parts whereby the above objects and certain other objects hereinafter appearing may be attained, as set forth in the following specification and particularly pointed out in the claims.

30 Referring to the drawings:

Figure 1 is a front elevation of a battery of furnaces, preferably two, embodying my invention.

Fig. 2 is an underneath plan view of the 35 grate embodying my invention shown in connection with a furnace, portions of said furnace being broken away to save space in the drawing.

Fig. 3 is a sectional elevation taken on 40 line 3—3 of Fig. 2 illustrating the grate-bars in their normal positions in full lines and in their uppermost feeding positions in dotted lines.

Fig. 4 is a sectional elevation taken on 45 line 4—4 of Fig. 2 illustrating the grate-bars swung downwardly to their dumping positions.

Fig. 5 is a sectional elevation taken on line 5—5 of Fig. 2.

50 Fig. 6 is a detail perspective view of one of the grate bars.

Fig. 7 is a perspective view of the lever by means of which one set of grate-bars is adapted to be manually operated.

Fig. 8 is a perspective view of the lever 55 by means of which the clinker grate is adapted to be manually operated.

Like numerals refer to like parts throughout the several views of the drawings.

In the drawings, 10 is a furnace of a well-known type comprising a boiler 11 and a combustion chamber 12 within the side walls 13, front 14 and bridge 15 of said furnace. Within said combustion chamber is located a grate 16 which embodies my invention and 60 consists of a plurality of series of grate-bars 17 and 18, the grate-bars of each of said series being arranged side by side or in parallelism and each grate-bar 19 being pivotally arranged to swing about a horizontal 65 axis extending transversely of said furnace or combustion chamber adjacent the rear side of said grate-bar.

The grate 16 also includes a frame arranged in said combustion chamber, said 70 frame consisting preferably of a plate 21 located within and against the front wall of said combustion chamber, while another plate 22 extends across said combustion chamber adjacent the bridge 15. The frame further- 75 more includes a plurality of longitudinally arranged supports 23 which are supported at opposite ends by the plates 21 and 22 respectively and preferably in pockets or recesses 24 within which they are held by keys 80 25 interlocking with lugs 26 which unite to form said recesses, said keys being removably mounted on said plates permitting said longitudinal supports to be quickly detached 85 therefrom.

The forward plate 21 is preferably rigidly secured in position at the front as stated, while the back plate 22 is mounted upon jacks 27 by means of which said back plate may be raised and lowered, as desired, to 90 vary the inclination of the grate in order that the feeding of fuel along said grate may be advanced or retarded as desired, said jacks being constructed in accordance with any of the well known types.

100 The longitudinal supports 23 are provided with recesses 28 within which trunnions 29, formed at opposite ends of the grate-bars 19, are adapted to fit and rotate, said trunnions constituting the pivots for said grate-bars 105 and as hereinbefore stated are arranged at the rear sides of said grate-bars.

The upper faces 32 of the grate-bars 19

are preferably flat and are normally positioned on a level with the upper faces of the plates 21 and 22 and the longitudinal supports 23, while the space between said plates 21 and 22 is substantially taken up by said grate-bars. Plates 30 are secured to the longitudinal supports 23 over the recesses 28 to prevent fuel and dirt from gaining access thereto and retarding the operations of said 16 grate-bars.

Each of the grate-bars 19 is made hollow to reduce the weight and expanse in manufacture and substantially in the form of a sector in cross section, the forward side 31 15 thereof being substantially concentric with the axis of said grate-bar and of sufficient depth to extend below the upper face of the adjacent grate-bar, when said grate-bar is elevated to its maximum height.

20 Slots 33 and 34 are provided in the upper face 32 and the forward side 31 respectively of each of said grate-bars and constitute draft slots, the number of said slots being varied according to the grade of fuel 25 used and the amount of draft provided. In the present instance however the slots are far apart and narrow to accommodate soft coal and forced draft.

The under sides of the grate-bars 19 are 20 substantially open to permit ashes, which sift through the slots 33 and 34, to escape. The rear sides 35 of the grate-bars 19 are also curved substantially following an arc whose center coincides with the axis of said 35 grate-bar, thus permitting said grate-bars to be placed substantially near together and swung upon their pivots without interfering one with the other.

Means have been provided to automatically swing said grate-bars about their respective axes, said means being preferably connected to said bars in such a manner that alternate bars will be successively elevated, while the intermediate bars remain flush 45 with the upper surface of the grate, the result of which movement causes fuel resting upon the grate-bar, which is to be elevated, being thrown upon the intermediate bar, owing to the inclination of the upper faces 50 of said swinging grate-bar and as said grate-bar is dropped to its horizontal position the alternate intermediate bars are likewise elevated to advance the fuel another step, and so on until the fuel has completed 55 its passage from one end to the other of the grate.

To accomplish this result, arms 36 are provided for each of said grate-bar, said arms depending therefrom and connected 60 together in such a manner that alternate grate-bars will be moved simultaneously as one set and the intermediate or remaining grate-bars as another set.

To elucidate the arrangement of said arms 65 and their connections the first set of grate-

bars will be designated "a", while the second or intermediate set are designated "b". The arms 36 of the grate-bars "a" are connected together by a link 37, while the arms depending from the grate-bars "b" are connected together by a link 38, while to said links, preferably at their inner ends, are secured rods 39 and 40 respectively, said rods extending outwardly through slots 41 in the front wall 14 of said furnace and preferably project a substantial distance therebeyond.

Teeth 42, preferably four in number are provided upon each of said rods 39 and 40, which teeth are arranged to be successively engaged by teeth 43 formed upon a collar 44, which in turn is mounted upon a shaft 45 journalled to rotate adjacent the front wall of said furnace, said shaft extending transversely of said furnace and said rods.

There are preferably two series of teeth 43 upon said collar 44, one series of which is adapted to aline with the rod 39, while the other series is arranged to aline with the rod 40, said series being arranged in such relation relatively to each other that as said collar is rotated, one of said rods will be reciprocated through the slot 42 in said front wall until the forward edges of one of said sets of grate-bars has been elevated to its maximum height after which the rod for said set will be released permitting said grate-bars to fall to their normal positions and the rod for the other set of said grate-bars may be reciprocated by its respective teeth in the same manner.

A rotary motion is imparted to the shaft 45 by any suitable means, but I have preferably shown in connection with the furnace 10, an engine 46 which is operatively connected thereto and adapted to continuously rotate said shaft. By extending the shaft 45 transversely of the furnace it will be evident that a large number of sections may be connected therewith and operated by the same engine and in the same manner. When such is the case and more than one boiler is connected thereto, or in a case where two series of grate-bars are employed in one furnace, as illustrated in the drawings, it is often desirable to operate one series independently of the other and to provide for such an emergency the collar 44 is slidably arranged on the shaft 45 and prevented from rotating relatively thereto by a key 47 arranged to slide in a slot 48.

A lever 49 is pivoted in the front wall 14 of said furnace, the free end of which is adapted to engage an annular groove 50 in said collar. A handle 51 is secured to said lever 49 outside of said wall 14 by means of which said lever may be rocked to move the teeth 43 into or out of engagement with the teeth 42 on the rods 39 and 40.

Stops 52 are provided upon the outside 130

of said wall 14 to limit the movements of said handle and thus accurately position or aline said teeth 42 and 43.

The instrumentalities hereinbefore described for moving said grate-bars are solely for the purpose of elevating the same to automatically feed the fuel along said grate.

It often becomes necessary however to operate the device by hand to feed the fuel or break up the clinkers, or furthermore to dump the entire fuel from the grate into the ash pit 53.

To facilitate this operation the arms 36 on the grate-bars are arranged substantially in front of the axis thereof, thus permitting said grate-bars to be rocked about said axes without said arms striking the forward side 31 of the adjacent bar. The rods 39 and 40 as hereinbefore described extend to the front wall of said furnace and project a substantial distance therebeyond and these rods are pivotally connected to levers 54 and 55 respectively, said levers being pivoted at their lower ends upon brackets 56 preferably secured to the front of said furnace.

In mechanically operating the several grate-bars the positions of the rods 39 and 40 with relation to a horizontal plane are constantly changing, due to the oscillatory movements of the ends of the arms 36, which movement would ordinarily result in throwing the teeth 42 and 43 out of engagement.

To prevent such an occurrence said rods have been connected to their respective links at points as far from the shaft 45 as possible, which point is substantially at the rear of the combustion chamber 12, while to still further aid in this particular function the outer ends of said rods have been connected to their respective levers 54 and 55 by studs 57 which are arranged to slide in slots 58 in said levers. This sliding movement is governed by the slots 41 in the front wall 14 of said furnace through which said rods are adapted to reciprocate, said slots 41 being of such a length that as the inner ends of said rods 39 and 40 are elevated by the rocking of said grate-bars upwardly, as shown in dotted lines Fig. 3, the studs 57 at the opposite ends of said links will be permitted to fall slightly, by their respective levers, until the lower end of said slot 41 is reached, which movement partially compensates, at a point beneath the shaft 45, for said upward movement of the inner end of said links, thereby maintaining the teeth 42 substantially at a uniform distance from the center of the axis of the shaft 45, while said teeth are in engagement with the teeth 43.

It is important that the upper faces 32 of the grate-bars be prevented from dropping below the level of the upper surface of the grate during the normal operation thereof, therefore stops 60 have been provided, these stops being pivotally mounted upon the

brackets 56 and arranged to be swung into and out of positions engaging said levers.

When said stops engage said levers, as in Fig. 3, said levers are permitted to move inwardly toward the front wall of said furnace only to the point where said upper faces 32 aline with the upper surface of the grate. Said stops are adapted to be swung from the positions indicated in Fig. 3 in full lines to that shown in dotted lines in said figure, 75 whereupon said levers 54 and 55 may be moved toward and into contact with said front wall or at least in contact with stops arranged at suitable points on said wall, as indicated in Fig. 4.

In the front wall 14 of the furnace are provided openings 61, one for each series of grate-bars, through which fuel may be supplied to the fuel chamber 62 at the front end of said grate. Doors 63 are pivotally mounted on said front wall adapted to close said openings, said doors also having openings therethrough which may be covered by plates 64, as shown in the lefthand furnace in Fig. 1, or hoppers 65 may be attached to said doors to assist in the automatic feeding of the fuel to the fuel chamber 62.

As the fuel is fed into the fuel chamber 62 it is deposited upon a bar 66 similar to the grate-bars 19, although somewhat shorter and minus the slots 33 and 34. This bar constitutes the feed bar and is pivotally supported in the plate 22 to swing about an axis extending longitudinally of the rear side of said bar. A stop 67 prevents the rocking or 100 swinging of said bar 66 below the level of the grate as it is never necessary or desirable to dump the fuel which is unused into the ash pit, the only purpose of said grate being to feed the fuel from said fuel chamber 105 to the first grate-bar of the series.

The bar 66 is also provided with a depending arm 68 which is adapted to be detachably connected to one of the rods 39 and 40, preferably the latter, by a pivoted arm 69 110 which is arranged to be swung into and out of a recess 70 formed at the lower end of said arm 68, thus when the rod 40 is reciprocated to oscillate the grate-bars connected therewith between the full line positions and 115 the dotted line positions thereof, as shown in Fig. 3, the grate-bar 66 may likewise be oscillated to feed fuel from the fuel chamber to the grate-bars 19, and furthermore by this connection between said feed bar 66 and said rod, said feed bar will be positively returned to its normal or full line position in said figure by the combined weights of the several grate-bars connected to said rod. To operate the grate-bars connected to the rods 125 40 to dump the fire the arm 69 is removed from the recess 70.

At the rear end of the grate 16 and next to the plate 22 is arranged a clinker grate-bar 71, similar in construction to the grate- 130

bars 19, but reversed to bring the trunnions 72 thereof at the front side of said grate-bar instead of at the rear, said trunnions engaging recesses 73 in the longitudinal supports 23 which are covered by the plates 30. The upper face 74 of this grate-bar is normally arranged to align with the upper faces 32 of the grate-bars 19, but may, when desired, be swung downwardly upon its pivot 10 to the position indicated in dotted lines Fig. 3, to discharge the clinkers therefrom into the ash pit 53, or said grate-bar may be swung upwardly, as in Fig. 4, to break up the clinkers which have collected at the end 15 of said grate and against the front face of the bridge 15.

A rocking movement is imparted to said clinker grate-bar by a rod 75 pivotally connected to an arm 76 depending from said 20 bar, said rod extending forwardly through the front wall of said furnace to a lever 77 with which said rod is connected in a manner similar to that in which the rods 39 and 40 are connected with their respective levers. 25 The operation of said clinker grate-bar however is independent of the grate-bars 19 and by manual means alone, the proper position thereof relatively to said grate and when in operation, being maintained by a 30 hook 78 pivoted on a bracket 79 upon which the lever 77 is mounted, said hook being arranged to engage a pin 80 on said lever, as illustrated in Fig. 8, or to be swung rearwardly and disengaged from said pin as in 35 Fig. 4 to permit the rocking of said lever.

The general operation of the device is as follows:

Fuel is introduced to the fuel chamber 62 through the opening 61 and deposited upon 40 the feed bar 66, which at this time is in the position illustrated in full lines Fig. 3. The engine 46 is set into operation to rotate the shaft 45, whereupon the teeth 43 are moved to engage the teeth 42 and first one and then 45 the other. The rods 39 and 40 may be reciprocated to rock its set of grate-bars from the positions shown in full lines Fig. 3 to the positions shown in dotted lines in said figure to feed the fuel lengthwise of the 50 grate or evenly distribute said fuel throughout said grate.

In case it is desired to advance or retard the fire over one or the other series of grate-bars, the handle 51 and lever 49 of that 55 series may be rocked, as hereinbefore described, to move the collar engaged thereby and disconnect the teeth 42 on said collar from the teeth on the rods adjacent thereto, thus permitting said rods to be manually 60 operated through the instrumentalities of the levers 54 and 55, or should it be desired to dump the fire on that particular grate, the stop 60 may be moved from the full line 65 position, Fig. 3 to the dotted line position, and said levers 54 and 55 moved from the

position in full lines in Fig. 3 to that in full lines Fig. 4.

Each of said series of bars are arranged to operate mechanically or by manual means, thereby permitting the fire in each of said 70 furnaces to be regulated and adjusted at will and a uniform depth of fuel to be maintained throughout the length and breadth of said grate. It will also be obvious that the alternate pivotal movements of the several 75 sets of grate-bars to feed the fuel from one to the other will assist in breaking up or loosening up the clinkers which may be formed thereon or to agitate the fuel to such a degree that said clinkers will not have a 80 chance to form. Furthermore the arrangement and construction of the various elements of the device permit the quick displacement of said elements in case of breakage. 85

The feeding of fuel from the hoppers at the front to the rear end of the grate will, by the use of the device hereinbefore described, be automatic for as the fuel or ashes is piled up at the rear end of the grate to a point above the highest point reached by the last grate bar in said series, the fuel on said last grate-bar, during the upward movement thereof, will be forced therefrom over the front side of said bar to the preceding 90 bar and so on from one to the other toward the front of said furnace, and as no fuel at such a time will be fed forward by the feed bar, owing to the action just described, it will be obvious that no new fuel will be fed 100 from the hopper to the fuel chamber until it is required.

Having thus described my invention what I claim and desire by Letters Patent to secure is:

1. A furnace having, in combination, a series of grate-bars arranged in parallelism, each of said bars being pivotally supported to swing about an axis disposed adjacent to the rear sides of said grate-bars and extending transversely of said furnace, an arm depending from each of said grate-bars substantially forward of said axis, links connecting the arms of alternate grate-bars together and forming independently operable sets, a rod connected to each of said links, said rods extending forwardly through the front wall of said furnace, and an operating lever pivotally connected with each of said rods, whereby said alternate sets of grate-bars may be respectively operated either upwardly to feed fuel longitudinally of said grate or downwardly to dump said grate. 115

2. A furnace having, in combination, a series of grate-bars arranged in parallelism, each being pivotally supported to swing about an axis extending transversely of said furnace, an arm on each of said grate-bars, links connecting the arms of alternate grate-bars together and forming independently 125 130

operable sets, a rod pivotally connected to each of said links, said rods extending forwardly to the front wall of said furnace and slidably engaging said wall, a plurality of 5 teeth on said rods, a rotary shaft, means on said shaft adapted to alternately engage teeth on said rods to swing alternate sets of grate-bars successively upwardly step by step, and means to disengage said operating 10 means from said teeth.

3. A furnace having, in combination, a series of grate-bars arranged in parallelism, each being pivotally supported to swing about a longitudinal axis extending transversely of said furnace, an arm on each of said grate-bars, links connecting the arms of alternate bars together and forming independently operable sets, a rod pivotally connected to the rear portion of each of said 15 links, a plurality of teeth on said rods, a rotary shaft, a plurality of collars mounted on said shaft adapted to be moved thereon into and out of alinement with the teeth on said rods, said collars each having teeth 20 thereon adapted to engage teeth on said rods and impart an intermittent upward swinging movement to said grate-bars, and means to move said collars and their teeth into and out of alinement with the teeth on their 25 respective rods.

4. A furnace having, in combination, a series of grate-bars arranged in parallelism, each being pivotally supported to swing about a longitudinal axis extending substantially transversely of said furnace adjacent the rear sides of said bars, an arm on each of said grate-bars, links pivotally connecting the arms of alternate grate-bars together to form a plurality of sets of grate-bars, a rod 35

pivotally attached to each of said links, a series of levers pivotally arranged at the front wall of said furnace, each of said levers being connected to one of said rods and adapted to be manually rocked outwardly to elevate the front sides of said 40 grate-bars to feed fuel from the front toward the rear of said furnace, stops adapted to normally engage said levers to limit the inward movements thereof and aline the upper faces of said grate-bars one with the other, said stops adapted to be moved to permit an additional inward movement of said levers, whereby said grate-bars may be swung downwardly from their normal positions to discharge the fuel therefrom. 45

5. A furnace grate comprising a series of grate-bars arranged in parallelism, each being pivotally supported to swing about a longitudinal axis adjacent one side thereof, a plurality of supports extending longitudinally of said furnace adapted to support said grate-bars, plates extending transversely of said furnace adjacent to the opposite ends of said longitudinal supports, lugs on said plates forming recesses adapted to 50 receive the ends of said longitudinal supports, and keys placed beneath said supports interlocking with said lugs and removably mounted thereon adapted to support said longitudinal supports within said recesses. 55

In testimony whereof I have hereunto set my hand in presence of two subscribing witnesses.

VASIL MACKAY.
